UNITED STATES PATENT OFFICE

LAURITS DINESEN, OF MINNEAPOLIS, MINNESOTA

SELF-CONTAINED VACUUM TANK AND PUMP

Application filed November 25, 1931. Serial No. 577,179.

My invention provides a simple and highly efficient self-contained vacuum tank, pump and motor, especially designed and adapted for use in connection with milking machines, but adapted, nevertheless, for more general use.

Generally stated, the invention consists of the novel devices, combinations of devices and arrangement of parts hereinafter described and defined in the claims.

In the accompanying drawing, which illustrates a commercial form of the invention, like characters indicate like parts throughout the several views.

15 Referring to the drawing:

Fig. 1 is a view chiefly in side elevation, but with some parts in vertical section showing the complete self-contained device;

Fig. 2 is a perspective showing a portion 20 of the pump casing, of the vacuum tank base, and the connected parts;

Fig. 3 is a fragmentary detail in section taken on the line 3—3 of Fig. 2; and

Fig. 4 is a section taken on the line 4—4 25 of Fig. 1.

The vacuum pump shown is of the two or opposed cylinder type and the casing thereof is indicated by the numeral 5. This casing is provided with a suitable base 6 adapting it to be rigidly secured to the floor or to a supporting tank or shelf. The pump casing is provided with a centrally located upstanding pump suction tube 7, which, as shown, rises from a boss 8 formed on the top of the 30 casing and through which air is drawn to the cylinders of the pump. Also the casing is provided with an air discharge port 9 shown as afforded by an elbow 9 having a perforated air discharge cap 10.

40 A tank suction tube 11 is shown as connected by an elbow 12 to the interior of a flanged pan-shaped vacuum tank base 13. This base 13 has a central hub 14 placed loosely around the lower portion of the 45 pump vacuum tube 7, as shown in Fig. 1.

A motor-supporting shelf 15 is detachably but rigidly secured to and on top of the pump casing 5. This shelf, as shown, has a perforated end which surrounds the base of 50 the tube 7 and is pressed onto the boss 8 by

the hub 14. A nut 16 has threaded engagement with the base portion of the tube 7 and with the interior of the boss 8, and when tightened, securely clamps the perforated end of shelf 15 between the boss 8 and hub 14. Suitable gaskets 16^a are interposed between nut 16 and hub 14 to render the tank air-tight. To further support the extended portion of the shelf 14 it is provided with a foot-forming flange 17 that is notched to fit the flanged top of the pump casing. Here it will be noted that the cylinders of the pump casing are symmetrically flanged and formed in their top portions so that the foot 17 will fit the flanged top of either cylinder, 60 thereby adapting the shelf to be supported either as shown in Fig. 1, or when turned 180 degrees to the left. The pump is arranged to be driven by an electric motor, the casing 18 of which is formed with a flanged 70 base 19 shown as secured to the shelf by nut-equipped bolts 20, which as shown, are passed through said flanged base, through the shelf and through the flanged top of the foot-forming flange 17. The rotor of this 75 motor drives the vacuum pump through a belt 21. The pump illustrated may and preferably is the type of pump disclosed and claimed in my prior Patent No. 1,632,436, entitled "Reciprocating pump" issued of date 80 June 14, 1927.

The vacuum tank 22 which is preferably made of sheet steel is an inverted drum with closed upper end and open lower end of a diameter adapting it to be telescoped 85 into the flange of the base 13. Somewhat above its lower end, this tank is provided with an outstanding annular flange 23 and between this flange and the top of the flange of the base 13 is placed a pliable gasket 90 24. The tank is thus gravity-seated in such manner that under partial vacuum or suction from within the tank, the gasket will be placed under increased pressure and the air-tight joint will be insured. Otherwise 95 stated, the greater the suction or vacuum the tighter will be the joint between the tank and the base.

Under the operation of the pump, air will 100 be drawn through the tank through the pipe

11, and from the tank to the pump, through pipe 7, and under continued use, there will be a water-condensation that will be caught in the tank base and held as long as the 5 pump is in operation. To automatically permit a discharge of the condensed water from the base of the tank whenever the pump stops and the pressure in the tank is restored to atmospheric pressure, I provide 10 an automatic drain device which, as shown, includes a short drain tube 25, shown as screwed into a perforated boss formed in the bottom of the base 13. At the lower end of this drain tube 25 is a valve 26 shown as 15 carried by one end of a lever 27 that is loosely pivoted at 28 to a lug on the lower end portion of the tube 25. This lever 27 is provided with a small weight 29 that keeps the lever 27 approximately horizontal and 20 with the valve 26 (which is preferably a pliable washer) slightly spaced from but very close to the extreme lower end of the drain tube 25. With this arrangement, initial suction or partial vacuum within the 25 tank 22 will cause valve 26 to tightly close the lower end of the drain tube 25 and such partial vacuum or suction will hold said valve closed as long as there is vacuum within the tank.

20 As soon as the pressure within the tank is restored to atmospheric pressure or nearly thereto, valve 26 will automatically open and permit the water to be drained from the tank base. As already indicated, air 35 drawn from the tank through the pump will be discharged through the elbow 9 and nozzle 10.

The suction tube 11 will be connected to the apparatus or place where partial vacuum is used to operate vacuum-actuating devices. When used in connection with a milking apparatus, the pipe 11 will be extended or be connected to the vacuum chambers or 40 vacuum-operating devices of the milking apparatus.

The device described is a complete self-contained pump, tank and power unit capable of being assembled at the factory and shipped ready for use and, in actual practice, has been found highly efficient for the purposes had in view, and especially for use in connection with milking apparatus.

What I claim is:

1. A self-contained vacuum-producing 55 unit comprising a vacuum pump with upstanding suction tube, a tank base applied around said suction tube, a motor-supporting shelf having a perforated end applied around said suction tube and clamped between said tank and base and an adjacent part of the pump casing, a motor mounted on said shelf and having connections for driving said pump, and an inverted vacuum tank having an open lower end gravity-seated on said tank base and arranged to

be seated with increased pressure by suction or partial vacuum produced in said tank when said pump is in operation.

2. The structure defined in claim 1 in which said pump has diametrically aligned oppositely projecting cylinders in symmetrical arrangement and in which said shelf has a supporting foot flange constructed to fit the top of either of said cylinders adapting the shelf to be supported in either of two 75 positions.

3. A vacuum-producing unit comprising a pan-like tank base, a tank gravity-seated on the rim of said tank base, a suction tube extended through said base and upward into 80 said tank to a point above the rim of said tank base, and means connected to said suction tube for producing partial vacuum in said tank, and a service suction tube connected to said base and communicating with 85 the interior thereof.

4. The structure defined in claim 3 in which said tank base is provided with a suction-closed pressure-opened drain valve.

5. The structure defined in claim 3 in 85 which said tank is provided with a lower portion telescoped into said base and serving to center the same in respect to said base.

In testimony whereof I affix my signature. 90
LAURITS DINESEN.
